TOY TRAIN OF DUCKS

Joseph Daniel Simon, 22 Midwood Cross,
East Hills, N.Y.

Filed Apr. 4, 1968, Ser. No. 11,298

Term of patent 7 years

(Cl. D34—15)

FIG. 1

FIG. 2

FIG. 5

FIG. 6

FIG. 4

FIG. 7

FIG. 1 is a perspective view of a toy train of ducks showing the design.

FIG. 2 is a top plan view showing the front duck of the train.

FIG. 3 is a front elevation of the design form shown in FIG. 2.

FIG. 4 is a rear elevation of the design form shown in FIGS. 2 and 3.

FIG. 5 is a top plan view of either of the duck forms following the front one, both of said following forms being alike.

FIG. 6 is a front elevation of FIG. 5.

FIG. 7 is a rear elevation of FIG. 5.

The toy train of ducks claimed has been shown in separate forms in FIGS. 2 through 7 for convenience of illustration.

I claim:

The ornamental design for a toy train of ducks, as shown and described.
